FIG.1.

FIG.2.

FIG.3.

FIG.4.

FIG.5.

FIG.6.

FIG.7.

FIG.8.

FIGURE 1 is a top plan view of one embodiment of a room air heater embodying my new design;

FIG. 2 is a front elevational view thereof;

FIG. 3 is a side elevational view, partly broken away, thereof;

FIG. 4 is a fragmentary bottom view thereof;

FIG. 5 is a top plan view of another embodiment of the design disclosed in FIGS. 1-4;

FIG. 6 is a front elevational view thereof;

FIG. 7 is a side elevational view partly broken away, thereof; and

FIG. 8 is a fragmentary bottom view thereof.

The side and rear views and portions of the bottom not shown are substantially flat.

The dominant features of my design reside in the portions shown in full lines.

I claim:

The ornamental design for a room air heater, as shown and described.
